UNITED STATES PATENT OFFICE.

ELFORD F. DOOLITTLE, OF TORRINGTON, CONNECTICUT.

BREAD-WRAPPER-SEALING MACHINE

1,129,963.

Specification of Letters Patent. Patented Mar. 2, 1915.

Application filed June 15, 1914. Serial No. 845,061.

To all whom it may concern:

Be it known that I, ELFORD F. DOOLITTLE, a citizen of the United States, residing at Torrington, county of Litchfield, State of Connecticut, have invented an Improvement in Bread-Wrapper-Sealing Machines, of which the following is a specification.

This invention has for its object to provide a simple and inexpensive machine for end and bottom sealing the wrappers of loaves of bread.

It is of course well understood that custom requires that loaves of bread be independently wrapped in wax paper. The sheets of paper after being wrapped about the loaves require to be secured which has been done both by the use of string and by heating the wrappers and melting the wax therein so that the flaps of the wrapper will adhere together. This sealing operation has been heretofore performed, so far as I am aware, by complicated and expensive machines requiring either gas or electric connections. In lieu of these complicated machines I have devised a machine so simple in construction and operation that it can be produced at trifling expense, cannot get out of repair and can be used by any person skilled or unskilled, thus placing it within the reach of small bakers and enabling them to effect an important saving of time and expense over tying the wrappers with string and enabling them to quickly and effectively seal each wrapper.

In the accompanying drawings forming a part of this specification, Figure 1 is a perspective of my novel machine; Fig. 2 a perspective of a loaf of bread wrapped and sealed; Fig. 3 a perspective of one of the slug holders detached; Figs. 4 and 5 detail views on an enlarged scale illustrating a simple and convenient means for detachably securing the slug holders to be sealing plates; Fig. 6 a transverse section of the machine on the line indicated by 6 in Fig. 1, looking in the direction of the arrow; Fig. 6^a a detail view corresponding therewith showing a sealing plate inclined from the bottom outward instead of standing vertical to the bed; Fig. 7 a transverse section on the line indicated by 7 in Fig. 1, looking in the direction of the arrow; Fig. 8 a vertical section on the line indicated by 8-8 in Fig. 7, looking in the direction of the arrows, and Fig. 9 is an enlarged detail sectional view illustrating a practical mode

of constructing the slug holders and the drawer.

10 denotes the frame or body of the machine which may be made of wood and may be placed upon a table or otherwise conveniently supported. Over the frame and secured thereto is a bed 11 of sheet metal.

12 denotes the adjustable sealing plates between which the loaves of bread are passed endwise, and which may stand vertically to the bed, as in Figs. 1, 6 and 7, or may incline outward from the vertical plane, as in Fig. 6^a, depending upon whether the ends of the loaves to be operated upon are parallel to each other or inclined outward from each other. The sealing plates may be formed integral with or rigidly secured to bases 13 which are adapted to be moved inward or outward over the bed. The outer edges of the bases are attached in any suitable manner to carrying pieces 14, as by means of screws 15 which pass through top strips 16 and engage the carrying pieces. The carrying pieces have respectively right and left threaded engagement with shafts 17 which pass transversely through the frame and are held against longitudinal movement in any suitable manner as by means of collars 18 on the shafts which bear against plates 19 on the frame. The carrying pieces are shown as provided with metallic bearings 20 which are engaged by the threads of the shafts. One or both ends of the shafts are provided with finger wheels 21 for convenience in rotating the shafts to adjust the sealing plates toward or from each other over the bed.

In my novel machine the heating of the wrappers to effect end and bottom sealing thereof is effected by means of heated slugs 22 which are held in contact with the sealing plates and with the under side of the bed. These slugs may be made of any suitable material that will not part with heat too rapidly, for example bricks. As every baker must have an oven, it follows that the slugs may be heated therein without additional cost. The slugs for end sealing of the wrappers are placed in the holders 23, which are simply boxes with one side removed, which may be made of wood or metal as preferred and are lined with asbestos or other suitable heat resisting material, as indicated by 24 in Fig. 9. The slug holders may be attached to the sealing plates in any suitable manner. In the present instance I have

shown the holders as provided with headed pins 25 which engage slots 26 in the sealing plates and retain the holders in place, as clearly shown in Figs. 1 and 4. The slugs 5 project from the holders sufficiently to cause them to lie in close contact with the plates and impart heat thereto.

The bottom sealing of the wrappers is effected by means of slugs placed in a drawer 10 27 which slides in ways 28 secured to the frame. Springs 29 upon the ways act to raise the drawer and retain the slugs in contact with the under side of the bed, the frame being cut away as shown, to receive 15 the drawer. The drawer is preferably lined with asbestos or other heat resisting material in the same manner as slug holders 23.

The receiving end of the machine is toward the left, as seen in Fig. 1. It will be 20 noted that the sealing plates flare outward at their receiving ends to permit the wrapped loaves to be conveniently inserted. The operator places the wrapped loaves transversely between the sealing plates with 25 the bottoms of the loaves resting on the bed and the ends bearing against the sealing plates which are adjusted sufficiently close to each other to press the end flaps of the wrappers down tightly but at the same time 30 permitting the loaves to be pushed ahead as succeeding loaves are placed in the machine, the feeding being by hand. As the bottom folds of the wrappers pass over the portion of the bed directly over the drawer, they 35 will be heated by the slugs in the drawer sufficiently to melt the wax in the wrappers and cause the overlapping edge at the bottom to adhere to the ply of paper under it. The portions of the sealing plates contiguous 40 to slug holders 23 are heated by the slugs in the holders and the wax in the end flaps of the wrappers is melted and said flaps are caused to adhere to the flaps under them, as indicated in Fig. 2. Each wrapped loaf as 45 it is pushed forward to be sealed, pushes the loaves ahead of it forward between the sealing plates, which are extended some distance beyond the slug holders so that the relatively cool forward ends of the sealing 50 plates will partly cool the sealed end flaps

and the relatively cool portion of the bed forward of the drawer will partly cool the sealed bottom flap so that before the loaves pass from the machine, the sealings of the wrappers will have become sufficiently cool 55 and set to permit the loaves to be handled without danger of breaking open the sealings.

Having thus described my invention I claim:

1. A machine of the character described comprising a metallic bed, metallic sealing plates between which the wrapped loaves are passed, a drawer for heated slugs adapted to slide underneath the bed, and holders 60 65 for heated slugs having one side removed and adapted to be placed adjacent to the sealing plates with the slugs in contact therewith.

2. In a machine of the character described, the combination with a metallic bed and metallic sealing plates, of slugs adapted to be heated and holders for said slugs having one side removed, said holders being adapted to be placed adjacent to the surfaces 70 75 to be heated with the slugs in contact with said surfaces.

3. A machine of the character described, comprising a metallic bed, metallic sealing plates between which the wrapped loaves 80 85 are passed endwise, a drawer for holding heated slugs lying under the bed, ways for said drawer and springs in the ways whereby the drawer is raised to retain slugs in the drawer in contact with the bed.

4. A machine of the character described comprising a metallic bed, metallic sealing plates between which the wrapped loaves are passed and which are provided with slots and holders for heated slugs having headed 90 pins for engagement with said slots whereby the holders may be detachably secured to the sealing plates, for the purpose set forth.

In testimony whereof I affix my signature in presence of two witnesses.

ELFORD F. DOOLITTLE.
